UNITED STATES PATENT OFFICE.

GEORGE E. HATCH, OF MERIDEN, CONNECTICUT, ASSIGNOR TO THE MERIDEN FLINT GLASS COMPANY, OF SAME PLACE.

DESIGN FOR CUT-GLASS ARTICLES.

SPECIFICATION forming part of Design No. 14,117, dated July 24, 1883.

Application filed June 18, 1883. Term of patent 7 years.

To all whom it may concern:

Be it known that I, GEORGE E. HATCH, of Meriden, in the county of New Haven and State of Connecticut, have invented a new Design for Cut-Glass Articles; and I do hereby declare the following, when taken in connection with accompanying drawing and the letters of reference marked thereon, to be a full, clear, and exact description of the same, and which said drawing constitutes part of this specification, and represents a side view of a shade.

This invention relates to a design for the ornamentation of articles of cut glass, commonly called "glassware," and particularly to that class which are made in sets—that is, great variety of articles having the same characteristic ornamentation; and the design consists in the ornamentation of the surface, as shown in the accompanying illustration and hereinafter described. Upon the surface of the articles annular cuts are made equidistant from each other, and diagonally across these, and in opposite directions, other cuts are made, producing on the surface series of hexagonal-shaped figures, the angle of one such figure intersecting with the angle of the next, and the angles of one series also intersecting with the corresponding angles of the next series, whereby a triangular space is formed between two of the hexagonal figures of one series and one of the

hexagonal figures of the next series. Diametrically across the hexagonal figures, and at right angles to the respective sides, other cuts are made, said cuts continuing across the triangular intermediate figures from the apex of one angle to the center of the opposite side. The surface is thus ornamented by a series of hexagonal figures and intermediate triangular figures, as shown. This ornamentation applies to the various articles included in glassware or sets of glassware, such as sets including shades for the lighting-fixtures, as well as articles of table-service, whereby the entire glass in the apartment will all correspond. The surface of each section of the said hexagonal figures is cut with fine grooves, as shown; but this surface may be left plain or otherwise ornamented.

I claim—

The herein-described design for the ornamentation of articles of cut glassware, consisting of the series of hexagonal figures, the angle of one figure intersecting the corresponding angle of the next, forming intermediate triangular figures, and cuts diametrically across said figures at right angles to the sides of said hexagonal figures, substantially as shown and described.

GEO. E. HATCH.
